Patented Sept. 9, 1913.

Fig. 1.

UNITED STATES PATENT OFFICE.

LUTHER E. MORRISON, OF NEW YORK, N. Y., ASSIGNOR TO MERGENTHALER LINOTYPE COMPANY, A CORPORATION OF NEW YORK.

TYPOGRAPHICAL MACHINE.

1,072,763.

Specification of Letters Patent.

Patented Sept. 9, 1913.

Application filed February 28, 1912. Serial No. 680,411.

To all whom it may concern:

Be it known that I, LUTHER E. MORRISON, a citizen of the United States, and a resident of New York, county of New York, 5 and State of New York, have invented a new and useful Improvement in Typographical Machines, of which the following is a specification.

My invention relates to typographical 10 composing machines, such as linotype machines of the general organization represented in Letters Patent of the United States, No. 436,532, to O. Mergenthaler, wherein circulating matrices are released 15 from a magazine in the order in which their characters are to appear in print and then assembled in line, together with expanding spacers, the composed line transferred to the 20 face of a mold, the mold filled with molten metal to form a slug or linotype against the 25 matrices which produce the type characters thereon, and the matrices thereafter elevated and returned through a distributing 30 mechanism to the magazine from which they 35 started.

More particularly, the invention relates to 40 that class of typographical machines in which are employed type or matrices provided with two or more characters and devices by which the position of the type or 45 matrices may be varied so that each will present one or another of its characters in the line, as demanded. Such an arrangement is disclosed in Letters Patent to J. R. 50 Rogers, No. 615,909, although the present construction differs therefrom in various particulars which will be subsequently set forth more specifically. For instance, when 55 plural character type or matrices have been assembled at different levels, it has been customary to restore them to the same level before distribution, and in the said Letters Patent this leveling operation is effected by the employment of a retractable ledge or 60 support in the casting or first elevator. In other forms the leveling is effected at a subsequent point in the cycle of operations, which feature generically is also well known. Thus, sometimes the leveling is effected in 65 the transfer channel after the type or matrices pass from the first elevator and before they are moved into engagement with the 70 sustaining bar of the distributing or second elevator. Again, and as disclosed in the ap-

plication for Letters Patent of J. R. Rogers, 55 Serial No. 559,784, filed May 5, 1910, the type or matrices are transferred to the second elevator at different levels and are permitted to move to the same level therein. Or, as set forth in the application for Letters Patent of J. R. Rogers, Serial No. 673,886, filed January 27, 1912, the second elevator is formed not only to receive type or matrices at different levels but also to sustain them in this condition during their 65 journey to the distributing mechanism, means being provided in connection therewith whereby the type or matrices are brought to a common level after they leave the elevator and before they are delivered 70 to the distributing mechanism.

In the present instance, I specifically employ a second elevator to receive and sustain the type or matrices at different levels, and also means to receive and sustain them at 75 different levels when they are transferred from the elevator, and by which sustaining means they are delivered to the distributing devices while still at different levels. Although the means just described are the ones 80 specifically and preferably employed for the purpose, it is to be noted that they are not all essential for the carrying out of my invention, which in its broadest sense involves the delivery to the distributing devices of 85 matrices at different levels, whereby I obviate the necessity for first leveling them, as has been the case in the various instances already discussed. In another sense, this last described operation may be regarded as 90 the equivalent of leveling the type or matrices within and by the distributing devices, or after they have been transferred thereto and before their final distribution. These and other improvements are illustrated in the accompanying drawing in their preferred form by way of example and as 95 applied to a linotype machine, but obviously many changes and variations may be made therein and in their mode of application 100 without departure from the scope of the invention, and generally speaking I desire it to be understood that I do not limit myself to any specific form or embodiment except in so far as such limitations are specified in the claims.

Referring to the drawing: Figure 1 is a side elevation, partly in section and partly

broken away, showing the distributor box, the distributing devices, and the second elevator in operative relation thereto; Fig. 2 is a transverse vertical section through the distributor box, etc., taken substantially on the line 2—2 in Fig. 1, and Fig. 3 is a transverse vertical section through the second elevator, taken substantially on the line 3—3 in Fig. 1. The matrices X are formed in their upper 10 ears with the transverse notches or recesses X¹. Fig. 1 illustrates the position of the parts as the matrices are being moved from the second elevator F by the transfer device E into the distributor box D, and also 15 shows the individual and successive separation of the matrices and their delivery to the inclined plates B¹, the distributor bar or rail B and the screws A, this operation being effected by the lifting finger C carried 20 by the arm C¹, which is reciprocated by the arm C² and cam C³ on the end of one of the screws A. So far as described, these parts are or may be the same as those set forth in the various patents and applications already 25 referred to, and operate or may operate in the same manner. It will be noted that the second elevator F is formed with inwardly projecting ledges F¹ and F², which sustain matrices in their lower position, and with 30 similar inwardly projecting ledges F³ to engage the transverse notches or recesses X¹ to sustain matrices in their upper position. Similarly, the distributor box D is formed with ledges D¹ and D² to sustain matrices in 35 the lower position, and with ledges D³ to sustain them in the upper position. It is to be noted that the ledges D¹, D² and D³ of the distributor box D correspond in position with and practically serve as extensions of 40 the ledges F¹, F² and F³ of the second elevator F, in such manner that when the matrices are transferred from the latter to the former, their relative position and level is not altered or disturbed. The transfer 45 slide E is actuated yieldingly and tends to move the matrices against the lifting finger C, which is reciprocated to engage and elevate the forward or extreme matrix, all in the ordinary manner. The lifting finger C is shouldered or recessed at C⁴ to engage the 50 extreme matrix, but as it must now engage matrices at different levels instead of at a single level as heretofore, this recessed or shouldered portion is made of greater extent 55 so that there will be no liability to its passage under a matrix standing in the upper position, but it will always rest against the side of the forward matrix whether the latter be in its upper or lower position. In 60 view of the fact that the extent of throw of the lifting finger is always the same and governed by the action of the cam C³ on the arm C², it follows that the matrix will always be elevated to the same point and 65 into proper relation to the plates B¹ and

screws A, whether originally in its upper or lower position.

For the purposes of the present case, the distributing devices may be regarded as comprising and beginning with the means whereby the matrices are engaged at different levels and then delivered thereby to the other distributing means, the generic principle of my invention thus obviating the necessity for the leveling of the matrices before their delivery to the distributing devices. 70 75

As previously stated, I have shown my invention in preferred form by way of example, and obviously there will be many changes and variations therein and in their mode of application which will suggest themselves to those skilled in the art and still be comprised within its spirit. 80

Having thus described my invention, its construction and mode of operation, what I claim and desire to secure by Letters Patent of the United States, is as follows:—

1. In a typographical machine comprising type or matrices adapted to stand at different levels, distributing devices comprising separating means to act upon said type or matrices at any of such levels and bring them to a common level. 90

2. In a typographical machine comprising type or matrices, the combination of distributing devices comprising separating means, and means for presenting the type or matrices to the separating means at different levels, the said separating means acting to bring them to a common level. 95

3. In a typographical machine, the combination with means for supporting type or matrices at one level and other means for supporting them at a different level, of separating devices to act upon said type or matrices at either level. 105

4. In a typographical machine, the distributor box D provided with a plurality of supporting means to sustain the type or matrices at different levels therein, in combination with distributing devices to act on the type or matrices irrespective of their level. 110

5. In a typographical machine, the combination with means for sustaining type or matrices at different levels, of distributing devices comprising a lifting finger to elevate individually the type or matrices while standing at such levels. 115

6. In a linotype machine, the combination of means for sustaining type or matrices at different levels, distributing devices comprising a set of propelling screws, and means for presenting type or matrices directly from such different levels to the action of the same set of screws. 120

7. In a linotype machine, the combination of means for sustaining the type or matrices at different levels, with distributing devices comprising a reciprocating finger provided 130

- with a shoulder portion to engage and detach the individual type or matrices standing at such different levels.
8. In a typographical machine, the combination of the distributing mechanism and means for transporting and presenting type or matrices thereto at different levels, the said distributing mechanism comprising means to receive the type or matrices at such different levels and to bring them to a common level just prior to their final distribution.
9. In a typographical machine, the combination of distributing devices and means for transporting and delivering type or matrices thereto at different levels, said distributing devices comprising means for bringing the type or matrices to a common level in presenting them for final distribution.
10. In a typographical machine, the combination of distributing devices and means for delivering type or matrices thereto at different levels, said distributing devices comprising a distributer bar and a reciprocating finger to engage the type or matrices
- at different levels and to elevate them to a common level before their passage onto said bar.
11. In a typographical machine, the combination of the distributing mechanism comprising the distributer bar B and the propelling screws A, the distributer box D provided with supporting ledges to sustain the matrices at different levels, and the lifting finger C to engage the matrices when sustained by either of said ledges.
12. In a typographical machine, the combination of means for supporting the type or matrices at one level and other means for supporting them at a different level, with distributing mechanism comprising devices to act upon said type or matrices when supported at either level.
- In testimony whereof I hereunto set my hand this 27th day of February, 1912, in the presence of two attesting witnesses.
- LUTHER E. MORRISON.
